MERCHANDISING DISPLAY STAND

Carl E. Lindgren, Rockford, Ill., assignor to Amerock Corporation, Rockford, Ill.

Filed July 1, 1971, Ser. No. 159,101

Term of patent 14 years

Int. Cl. D6—04

U.S. Cl. D6—168

FIG. 1

FIG. 2

FIG. 3

FIG. 1 is a perspective view of a merchandising display stand incorporating my new design.

FIG. 2 is a side view of the stand as seen from the right in FIG. 1.

FIG. 3 is a top view of the stand.

FIG. 4 is a front view.

FIG. 5 is a fragmentary sectional view taken along the line 5-5 in FIG. 4.

FIG. 6 is an enlarged sectional view taken along the line 6-6 in FIG. 4.

I claim:

The ornamental design for a merchandising display stand, as shown.
